ATTORNEY

UNITED STATES PATENT OFFICE.

OSCAR C. KROSHAUG, OF VOLGA, SOUTH DAKOTA.

BEADING-TOOL FOR BOILER-TUBES.

1,278,685.

Specification of Letters Patent. Patented Sept. 10, 1918.

Application filed November 17, 1916. Serial No. 131,913.

To all whom it may concern:

Be it known that I, OSCAR C. KROSHAUG, a citizen of the United States, residing at Volga, in the county of Brookings and State 5 of South Dakota, have invented certain new and useful Improvements in Beading-Tools for Boiler-Tubes, of which the following is a specification.

This invention relates to metal working 10 tools, and, the invention has more particular reference to an improved beading tool for boiler tubes for forming the usual beading or flanged ends upon boiler flue tubes, whereby, the same will be secured to the flue 15 sheet.

As an object of equal importance, the invention aims to provide a tool which may be adjusted to various sizes of tubes, thus, permitting the device to be used for flanging 20 the ends of boiler flue tubes which vary in diameter.

Among other aims and objects of the invention may be recited, the provision of a beading tool for boiler-tubes of the character 25 mentioned, with a view to compactness, and in which the number of parts are few, the construction simple, the cost of production small, of efficiency and operation high.

Other improvements and novel details in 30 the construction and arrangement of parts will be appreciated from the detailed description to follow, which is to be read in connection with the accompanying drawings, forming a part hereof, and wherein I disclose 35 several preferred embodiments of the invention for the purpose of illustration.

In the drawings:

Figure 1 is a perspective of my improved 40 tool,

Fig. 2 is a section therethrough taken on the line 2—2 of Fig. 1,

Fig. 3 is a similar section showing a slightly modified form of tool,

Fig. 4 is a fragmental vertical section 45 through the preferred embodiment of the tool, and

Fig. 5 is a fragmentary side elevation of the tool, illustrating the same in use upon a tube and sheet, the latter element being 50 shown in section.

Similar characters of reference are employed in all of the above described views to indicate corresponding parts.

Referring now in detail to the drawings, 55 the present improvements may be said to em-

body a cylindrical mandrel 1, which has formed therein, in proximity to one end thereof, a recess 2, whereby a tube engaging hook 3, having a substantially rectangular base may be received thereby. It is to be noted, that one end of the hook 3 is cut away, as at 4. By so arranging the hook, engagement with the end of the boiler tube 10 will be facilitated and means will also be provided, whereby, the portion 11 as bent 60 backwardly from the tube, will be so formed as to constitute a beading or retaining flange, the same being engageable with the flue sheet 12, in order that the tube will be properly maintained in position. 70

A second recess 5, of a greater length than the recess 2 is formed in the opposite side of the mandrel 1 and receives the elongated strip 6. To adjustably secure the strip within the recess 5, a set screw 7 is passed therethrough and engaged with the threaded sockets 7' of the mandrel. A second set screw 8 is turned into engagement with the strip 6 and bears upon the body of the mandrel. By this arrangement, it is evident that 80 adjustment of the strip 1, inwardly or outwardly, is afforded, since both screws are carried near one end of the strip 6, and in this way the tool will be made to fit snugly in tubes of different sizes. Thus, should the 85 tool be used upon flues of varying diameters, the strip 6 can be readily adjusted so as to permit the portion 4 of the hook 3 to properly engage the marginal edge of the tube upon which the beading or flange is to be 90 formed. Since the set-screws are carried adjacent to one end of the strip, it is obvious that the opposite end of the strip will at all time be within the recess 5. However, the set-screws 7 may be adjusted within the 95 socket 7' to permit the end of the strip adjacent to which the screws are carried to be moved outwardly for a greater distance, and then the screw 8 is brought into a binding engagement with the mandrel within the recess 5 for constituting a jamming action and thus holding the strip against further movement in either direction. As the mandrel is reciprocated within a tube, it is obvious the strip having been adjusted to take up the 100 play within the tube will cause the side of the mandrel from which the tube-engaging hook 3 extends to be bearing firmly upon the tube. Therefore, as the mandrel is reciprocated the cut away portion 4 of the hook 110

will engage the tube and bend the same accurately as hereinbefore specified.

In Fig. 3, I have shown a slightly modified form of the tool, wherein, the mandrel 1 is provided with an integral hook 9, identical with the hook 3, thus, eliminating the necessity of securing the same in position and further, providing a device which will be exceedingly strong and durable.

10. In using the improved tool, the inner or elongated end of the mandrel 1 is inserted within a tube while the outer portion thereof, carrying the hook 3 may be gripped within the hand of the user. The tool is now reciprocated and the hook 3 thereof engaged with one end of the tube, consequently causing a portion thereof to be bent backwardly upon itself into engagement with the flue sheet and securely clamping the tube thereto.

15. By continuous pounding, a beading or flange is formed and will present a continuous and smooth surface, thereby lending to the durability of the completed construction.

It will be evident, that with the improved tool, the use of a hammer or other similar implement will be eliminated, inasmuch as the weight of the mandrel is sufficient to enable the delivering of a powerful blow to the end of the flue tube.

30. I claim:

1. A beading tool for boiler tubes comprising an elongated mandrel, a tube engaging hook carried by said mandrel and extending from one side thereof and an adjustable mounted strip supported upon the opposite side of said mandrel for holding the mandrel firmly in a tube as the same is being reciprocated and as said hook engages the end of the tube.

40. 2. A beading tool for boiler tubes comprising an elongated mandrel, a tube engaging hook extending from one side of said mandrel, said mandrel having an elongated recess formed in one side thereof, an elongated strip fitting within said recess, and means for moving one end of said strip inwardly and outwardly with respect to said recess, thus causing the strip to project beyond the surface of the mandrel for caus-

ing the mandrel to fit snugly within a tube 50 for permitting said hook to engage the tube.

3. A beading tool for boiler tubes comprising an elongated mandrel, a tube engaging hook engaging one side of said mandrel, said mandrel having an elongated recess 55 therein, an elongated strip fitting within said recess, said mandrel having a threaded socket communicating with said recess, a retaining screw passing through said strip and into said socket for adjusting said strip, and a jam screw passing through said strip and engaging the mandrel within said recess for holding said strip against possible movement, thus causing the mandrel to fit snugly within tubes of various sizes for causing 65 said hook to engage the end of the tube.

4. A beading tool for boiler tubes comprising an elongated mandrel, said mandrel having a comparatively deep short recess at one side thereof, a comparatively thick tube 70 engaging hook fitting within said recess and extending therefrom, said hook being thicker at one end than the opposite end, said hook having a cut away portion formed in the thick end thereof in alinement with 75 the side surface of said mandrel, said mandrel having an elongated recess formed in one side thereof opposite to the side to which the first mentioned recess is formed, and an elongated strip positioned within 80 said last mentioned recess, and set screws passing through said strip and engaging said mandrel within said recess for holding said strip in an adjusted set position, said strip being adapted to be moved outwardly 85 beyond the surface of said mandrel, thus causing the strip to take up the play of different sized tubes in which the mandrel may be positioned, thus causing said hook to be held in alinement with the tube for 90 engaging and bending the same.

In testimony whereof I affix my signature in presence of two witnesses.

OSCAR C. KROSHAUG.
